UNITED STATES PATENT OFFICE.

OTTO GOETZKE, OF JERSEY CITY, NEW JERSEY, ASSIGNOR TO EXCELLALL PRODUCTS COMPANY, OF NEW YORK, N. Y., A CORPORATION OF NEW YORK.

DESIGN FOR A TOP FOR CANS, BOXES, BOTTLES, OR SIMILAR ARTICLES.

49,180.

Specification for Design.

Patented June 13, 1916.

Application filed February 1, 1916. Serial No. 75,609. Term of patent 7 years.

To all whom it may concern:

Be it known that I, OTTO GOETZKE, a citizen of the United States, residing at Jersey City, in the county of Hudson and State of New Jersey, have invented a new, original, and ornamental Design for a Top for Cans, Boxes, Bottles, or Similar Articles, of which the following is a specification, reference being had to the accompanying drawing, forming part thereof, in which—

Figure 1 is a perspective view of a top for

cans, boxes, bottles or similar articles showing my new design. Fig. 2 is a plan view of the same.

I claim:

The ornamental design for a top for cans, boxes, bottles or similar articles, as shown.

OTTO GOETZKE.

Witnesses:

F. B. TOWNSEND,
REMINGTON SCOTT.
